Attorney

UNITED STATES PATENT OFFICE.

HERBERT CLAUSER, OF ELKTON, MARYLAND, ASSIGNOR TO VICTORY SPARKLER & SPECIALTY COMPANY, OF ELKTON, MARYLAND, A CORPORATION OF DELAWARE.

TORPEDO.

Application filed May 13, 1926. Serial No. 108,967.

This invention relates to torpedoes, and more particularly to the construction of toy torpedoes of the tube type.

It is a general object of the present invention to provide a novel and improved form of tube torpedo.

More particularly it is an object of this invention to provide, in a tube torpedo, novel means for closing the ends of the tube and for retaining the explosive compound within the same.

Another object of the present invention is to provide an inexpensive, simple casing adapted to receive an explosive charge, together with means for simply and effectively sealing the explosive in the casing, to thus insure an actual disruption of the same when the explosive compound is detonated, thus preventing initial escapement of gases and insuring a loud report.

Other and further objects of the invention will be more apparent upon a consideration of the accompanying drawing and following specification wherein are disclosed two exemplary embodiments thereof, it being understood, however, that various changes may be made therein by those skilled in the art without departing from the spirit of the invention as expressed in the appended claims.

30 In said drawing:

Figure 1 is a vertical central section through one form of torpedo constructed according to the present invention, and

Figure 2 is a similar view of a second form.

35 In the manufacture of toy torpedoes, the greatest difficulty confronting the manufacturer is the provision of a cheap and simply formed container for the explosive material, which can be readily closed and sealed after 40 being charged with the explosive material and gravel or other detonating means. Referring to the drawing, it will be seen that the present invention contemplates the provision of a simple straight tube 10 formed of 45 paper, cardboard or other suitable fibrous material which may be treated with any desired compound to render the same waterproof. The tube is preferably formed by rolling a thin sheet of the material, covered with adhesive, into a tubular form having ends cut off at right angles to the axis of the tube. It is to be understood that in transverse section 50 the tube may be circular, elliptical or of any other desired configuration. The tube may

be provided with an auxiliary bottom consisting of a single disk 11, as shown in Fig. 1, of such a diameter as to have a snug fit within the tube and to be frictionally retained in position during the charging operation. This disk is displaced a short distance 12 above 55 the bottom of the tube.

The tubes thus fitted are usually assembled in a tray with the open ends uppermost to receive the explosive charge, which may, and usually does, consist of sulphur, potassium chlorate and antimony. At the same time, a suitable quantity of gravel, small pebbles or other abrasive granules are charged into the tube to serve as elements to produce friction and percussion for exploding the composition. To close the top of the tube, it is provided with a disk 13 similar in construction and fit to the disk 11. The disks 11 and 13 65 may be formed of the same or similar material to that used to form the tube 10 and may 70 be waterproofed if desired.

The disk 13 is displaced inwardly from the upper end of the tube a distance 14 substantially the same as the distance 12 from which the disk 11 is spaced from the lower end of 80 the tube. The cup-like spaces beyond the outer faces of the disks 11 and 13 are then filled with a suitable adhesive, sealing compound 15. The material thereof must have certain characteristics to be suitable for use 85 in toy torpedoes. It must be sufficiently adhesive to stick to the inner walls of the tube 10, so that the disks 11 and 13 cannot be readily blown out of the tube upon explosion. It must preferably require but a short time for 90 drying and should not crack after being dried, nor should it expand or contract in unequal relation to the material forming the tube and disks. Furthermore, it should not shatter upon the necessary impact to explode 95 the torpedo, before the explosion takes place, and when shattered by the explosion should break into small pieces so as not to fly a great distance and injure bystanders. It should be waterproof and fireproof. The sealing composition forms no part of the present invention and need not be further described herein.

The purpose of the disks 11 and 13 is to retain the explosive composition and gravel in position during charging and while the ends are being sealed. Reliance need not be placed upon the frictional engagement of these disks with the walls of the tube, for they

may be coated on their edges with an adhesive, particularly the bottom disk.

The bottom disk receives the brunt of the rough treatment when the tube is being charged, and it may be found that owing to its small area of contact with the side walls of the tube that it may be displaced. To prevent this, it may be made in the form of a cup 17, as shown in Fig. 2, by pressing a larger disk into a suitable die to turn the edges 18 upwardly. These edges or side walls may be of any suitable height in order to present sufficient surface to the walls of the tube to receive the proper amount of adhesive material to insure the cup remaining in position during the charging and sealing operations. Beneath this cup is provided the same sealing composition 15 as in the case of Fig. 1, and preferably the top closure for the tube is a simple disk 13 as shown in Fig. 1, since immediately upon the application of this disk, the adhesive compound may be applied over the same, insuring its remaining in the proper position.

Having thus described the invention, what

is claimed as new and desired to be secured by Letters Patent is:

1. A torpedo casing consisting of an open ended tube; a disk within and closing each end of the tube; an explosive charge in the casing between the disks, and means filling the open ends of the tube for securing the disks therein.

2. A torpedo casing consisting of an open ended tube; a disk within and closing each end of the tube; an explosive charge in the casing between the disks, and adhesive filling arranged in the open ends of the tube for securing the disks therein.

3. In a torpedo, in combination, a fibrous container body in the form of an open ended tube, an explosive in said tube, means spaced inwardly from the ends of said tube to confine the explosive therein, and adhesive sealing means filling the remaining portions of the tube.

In testimony whereof I hereunto affix my signature.

HERBERT CLAUSER.
